UNITED STATES PATENT OFFICE.

ROBERT MIDDLETON, OF LEEDS, COUNTY OF YORK, ENGLAND.

IMPROVEMENT IN MACHINERY FOR STOCKING, UNHAIRING, AND SOFTENING HIDES.

Specification forming part of Letters Patent No. **221,246**, dated November 4, 1879; application filed May 31, 1879; patented in England, March 19, 1879.

To all whom it may concern:

Be it known that I, ROBERT MIDDLETON, of Leeds, in the county of York, England, have invented new and useful Improvements in Machinery or Apparatus employed for Stocking, Unhairing, and Softening Hides, Skins, or Leather, which improvements are fully set forth in the following specification, reference being had to the accompanying drawings.

My improvements in machinery or apparatus for stocking, unhauling, and softening hides, skins, and leather have the effect of rendering the machines capable of operating much more quickly upon the leather, hides, or skins, consequently doing a greater amount of work. By these improvements, also, the number of strokes of the machine or blows per minute upon the leather may be varied; also, the strength or force of the blows may be varied.

Figure 1 is a part longitudinal section, Fig. 2 a part transverse section, Fig. 3 a plan looking at the top, and Fig. 4 a front elevation of part of machine to be described hereinafter.

I place two steam-cylinders, *a a*, on a foundation-plate, *b*, side by side, so as to act direct upon the stock-feet *c c*, which are coupled to the end of the piston-rods *d d'* by means of ordinary cotters *e*, as shown. Motion is imparted to the pistons, which are within the cylinders and of ordinary construction, by steam, which is admitted thereto through ordinary slide-valves by means of a variable valve-motion, *f f'* being the valve-spindles, each being actuated by means of a sliding cam, *g*, through oscillating levers *h* and *i*. The required motion is transmitted to the cam from one of the piston-rods, *d*, through lever *j* and connecting-rod *k*. The motion of the cam *g* is varied by a self-acting ratchet arrangement.

Every stroke of the pistons carries the lever *j* with them, from which an intermittent motion is transmitted to the bevel-wheels *l* and *l'* through the ratchet-lever *m*, pawl *n*, and ratchet-wheel *n'*, the bevel-wheel *l* being fitted with sliding key onto the screw *o*, on which, also, is provided the nut *p*. On a rotary movement being given to the screw *o* a traverse motion is imparted to the nut *p*, which carries with it the ratchet-gearing, and lever *m* also varies the position of the end *k'* of the connecting-rod *k* in the slot *j'* of the lever *j*, which has the effect of varying the traverse of the cam *g*, and thence the motion of the slide-

valves employed for admitting steam into the cylinders; also, by this motion the steam is exhausted at variable points of the piston's stroke. The object of this variable movement is to cause the stroke of the stocks' feet to be more or less effective, consistent with the proper working of the leather, hides, or skins.

As well as the above automatic arrangement of varying the stroke, it may also be varied by the hand of the attendant.

In order to effect a regularity of stroke of both piston-rods *d* and *d'*, I apply a provisional tappet-motion on the piston-rod *d'*. The position of the clamp or tappet *q* may be adjusted and fixed in any required position on the piston-rod *d'*, and in the event of the stroke of the piston-rod *d'* differing from that of the piston-rod *d* the clamp or tappet *q* comes in contact with one of the collars *r* or *r'* on the rod *s*, which is mounted in suitable bearings, *t*, causing it thereby to move either right or left, which movement is transmitted to the slide-valve spindle *f'*, causing thereby the valve to be moved and the stroke of the pistons to be reversed. This arrangement only comes into operation when any irregularity occurs, and has the effect of preserving the stroke of each piston the same.

I also conduct the exhaust-steam into jacketed ends, *u*, of the frame-work, suitable openings being provided for the admission and exit of the same, and the steam supplies an inexpensive artificial heat to the stocks for the purpose of quickening the process.

Having now described the nature of the said invention, what I claim is—

1. In a machine for stocking, softening, and unhauling hides and skins, the combination of one or more stock-feet, *c*, the piston-rod *d'*, connected thereto at one end, a piston at the other end of the rod *d'*, the steam-cylinder *a*, steam-valve, and valve-operating mechanism, substantially as set forth, whereby the elastic force applied to reciprocate the stock-feet can be varied as required and as specified.

2. The combination, with the stock-feet *c c* and means for reciprocating the stock-feet, of the jacketed ends *u*, into which steam is introduced, substantially as set forth.

ROBERT MIDDLETON.
